UNITED STATES PATENT OFFICE.

CLARA ALICE HARRISON, OF LONDON, ENGLAND.

INCANDESCENT ELECTRIC LAMP.

1,247,956.

Specification of Letters Patent. Patented Nov. 27, 1917.

Application filed March 24, 1914. Serial No. 826,919.

To all whom it may concern:

Be it known that I, CLARA ALICE HARRISON, a citizen of the United Kingdom of Great Britain and Ireland, and resident of 5 14 Dickenson road, Crouch End, London, England, have invented certain new and useful Improvements in or Relating to Incandescent Electric Lamps, of which the following is a specification, such as will enable others skilled in the art to which it 10 appertains to make and use the same.

This invention relates to the renewing or refilling of electric incandescent lamps with wire or like filaments.

15 The essential feature of this invention is the use of spring clips which are independent of the leading-in wires, but can be inserted into a lamp to grip and hold such wires while they also grip the filament or 20 are connected thereto in any other convenient manner. As a modification connecting pieces may be used which are attached to the leading-in wires by a ring, hook or the like, while one or both of them grip the filament with a spring action. The clips are inserted into the lamp through a hole which is most conveniently made in the pip and may be enlarged if desired and after the 25 operation is finished the hole is closed in 30 any convenient manner.

In order to more fully explain my said invention I will describe the same with reference to the accompanying drawings, in which:—

35 Figure 1 shows a lamp having a hole, at its bottom, through which the filament has been removed; Fig 2 shows end and side views of a spring clip; Fig. 3 shows spring clips secured to leading-in wires, and a filament-end secured to one such clip; Fig. 4 shows the new filament in place and the aforesaid opening closed; Figs. 5 and 6 are views of a form of tool useful in fitting the spring-clips and the filament-ends in place.

40 Referring to Figs. 1 and 2, an old lamp may have the usual pip removed, and the resulting hole, at *a*, sufficiently enlarged to permit the pieces of a broken filament to fall therethrough.

45 Spring clips may then be inserted, through the hole mentioned, and secured to the usual leading-in wires *c*. Suitable spring clips are shown in Fig. 2, and each may consist of a coiled wire helix, *b*, having the 55 adjacent convolutions close together.

These clips are each intended to be sepa-

rately inserted into the lamp, by a suitable tool, and the adjacent convolutions sprung apart to grip therebetween the leading-in wires, *c*. One end of the new filament is 60 then passed into the lamp, and fitted between another pair of convolutions of the helix. It will be seen, therefore, that each clip is detachable from both the leading-in wire and the filament-end, and while it 65 holds the filament out of contact with the wire will form part of the circuit of the lamp when put into use.

It must be understood that the filament may be attached to the clips before they are 70 inserted into the lamp or after insertion, or to one clip before insertion and to the other after.

Fig. 4 shows a lamp like that in Fig. 3 in which the filament *d* has been passed over 75 the hooks *e* and attached by both its ends to the said clips. Any suitable tools may be employed to manipulate the clips and the filament; for example, the clips may be opened by inserting a blunt tool between the 80 coils so as to make an opening sufficiently wide to receive the leading in wires or the filament or both, as the case may be, after which the tool is removed and the spring clip closes upon the wire or filament, or 85 both.

Fig. 5 shows a tool comprising a handle *f* in which a tube *g* is fixed. This tube has a side opening *h* and has within it a slidable wire *i* one end of which projects through the 90 side opening and the other from the end of the tube.

In using this tool the end *i'* is put between the coil of the wire clip to hold it open and facilitate the insertion of the leading in wire 95 or the filament, or both. When the wire or filament is in the clip the end *i'* is withdrawn into the tube by pulling the wire at its end projecting through the opening *h* thus withdrawing the end *i'* from the clip 100 which then closes on the leading-in wire or filament.

As an example of the *modus operandi*, assuming a clip with one end of the filament is introduced into the bulb by the tool 105 and is connected to a leading-in wire; the tool is then removed and any suitable tool employed to place the filament over the hooks *e* after which the other leading-in wire and the other end of the filament are 110 connected together by another clip.

If a supporting wire is without a hook

it may be suitably bent to make a hook or equivalent to facilitate attaching the filament and for this purpose a tool such as shown in Fig. 6 may be used. This tool resembles that shown in Fig. 5 but the projecting end of the wire is hook-shaped, as at i^2 , so as to engage the end of a wire support in the lamp and form a hook on it.

What I claim and desire to secure by Letters Patent is:—

- 5 1. In an incandescent electric lamp, a leading-in wire; a detachable spring connecting means comprising a closely-coiled helix supported by the wire and grippingly 15 engaging the same between adjacent convolu-

lutions; and a filament gripped between other pair of convolutions of said helix.

2. In an incandescent electric lamp, a leading-in wire; a filament; and a spring means, detachable from both wire and filament, grippingly engaging both and holding the filament out of contact with the leading-in wire. 20

In witness whereof I have hereunto set my hand in presence of two witnesses.

CLARA ALICE HARRISON.
